UNITED STATES PATENT OFFICE.

JARVIS B. EDSON, OF ADAMS, MASSACHUSETTS.

FORMING AND FINISHING SURFACES COATED WITH ZYLONITE.

SPECIFICATION forming part of Letters Patent No. 269,240, dated November 27, 1883.

Application filed April 22, 1883. (Specimens.)

To all whom it may concern:

Be it known that I, JARVIS B. EDSON, of the town of Adams, in the county of Berkshire and State of Massachusetts, have invented new and useful Improvements in Forming and Finishing Surfaces Coated with Zylonite or Substances of a Similar Character, of which the following is a specification.

The invention consists in forming zylonite into a very thin sheet by the operation of cutting, the same as in the process of making veneer, and passing such thin sheet simultaneously through a pair of pressure-rolls or similar gradually-approaching surfaces, one surface 5 of the said thin sheet having been treated by a solvent of it immediately previous, to produce a tacky or sticky action of the same upon the surface to be coated while under pressure, as will hereinafter appear; or, in other words, 10 after the sheet of zylonite is formed—say, from two to five thousandths of an inch in thickness—whether formed continuously as from a roll, or in sheets as they may be sliced from a body or mass of the same, as in the process of 15 planing. I then introduce one end of the said sheet between a pair of pressure-rolls or similar advancing surfaces, simultaneously with the piece of fabric, such as cloth or other textile material or leather, or thin sheets of wood, 20 or any substance that it is desirable to have coated, and which exists in sheets; and immediately before starting the rolls I introduce, either by a brush or any suitable applying device, as a roll or a tube with jets, a sufficient 25 quantity of the solvent, as collodion, between the two surfaces, so that as the rolls begin to revolve or the pressure advances the said substance will be compressed between the two surfaces of material, and the surplus of the 30 fluid or solvent will be forced back, or prevented from passing through, on account of the close contact between the rolls or the pressure upon the substances so combined, the result of which action I have found, is that 35 the said solvent thus applied upon the surface of the zylonite or similar substance slightly dissolves the thin sheet without injuring the opposite surface, and allows its surface to be forced into the interstices or fibers of the fabric upon which it is held or pressed by the action of the rolls or their equivalent, and in

this way forms a perfect union between the two surfaces.

By making the sheets of zylonite exceedingly thin, as from one to two thousandths of an inch, and laying it upon figured fabrics—such as linen stuffs woven with figures—they may be coated in this manner without destroying the effect of the figures, and at the same time form a surface which is absolutely 55 impervious to water. I thereby produce a nice water-proof fabric, which may be used for wearing apparel, or for table-covers or cuffs and collars, &c., which may be washed off with soap and water when desired. In 60 such a case I have found it preferable that one of the rolls or pressing-surfaces should be made of rubber, so as to have a slightly-yielding action, in order not to destroy the figures upon the woven fabric. 70

It is evident that both sides of the substance may be covered, or that both sides may be finished, as desired, for any purpose whatever, either simultaneously or at separate operations, and from such sheets any articles may 75 be cut, as by dies or other convenient manner.

I therefore claim—

1. The method herein described of coating substances with zylonite, or its equivalent, which consists in introducing a thin sheet of 80 the zylonite and a sheet of the material to be coated between gradually-advancing surfaces, slightly dissolving the contact side of the zylonite, and then compressing the sheets between the gradually-advancing surfaces, substantially as described. 85

2. The method herein described of coating substances with zylonite, or its equivalent, which consists in introducing a thin sheet of 90 the zylonite and a sheet of the material to be coated between gradually-advancing surfaces, then introducing a solvent between the two sheets to slightly dissolve the surface of the zylonite, and then immediately compressing the sheets between the gradually-advancing 95 surfaces to disseminate the surplus solvent and unite the two sheets, substantially as described.

3. The method herein described of coating substances with zylonite, or its equivalent, which consists in introducing a thin sheet of 100 the zylonite and a sheet of the material to be coated between gradually-advancing surfaces,

one of which is yielding, then introducing a solvent between the two sheets to slightly dissolve the surface of the zylonite, and then immediately compressing the sheets between the 5 gradually-advancing surfaces to disseminate the surplus solvent and unite the two sheets, substantially as described.

4. As an article of manufacture, a sheet of fabric—such as cloth or other material—coated 10 on one or both sides with thin sheets of zylo-

nite, or its equivalent, through the medium of an interposed solvent, substantially as and for the purpose described.

In witness whereof I have hereunto subscribed my name and affixed my seal in the 15 presence of two subscribing witnesses.

JARVIS B. EDSON. [L. S.]
